UNITED STATES PATENT OFFICE.

UTLEY WEDGE, OF ARDMORE, PENNSYLVANIA.

FURNACE-DUST COLLECTOR.

1,165,351.

Specification of Letters Patent. Patented Dec. 21, 1915.

Application filed January 29, 1913. Serial No. 744,967.

To all whom it may concern:

Be it known that I, UTLEY WEDGE, a citizen of the United States, residing in Ardmore, Pennsylvania, have invented certain Improvements in Furnace-Dust Collectors, of which the following is a specification.

My invention relates to apparatus employed for separating from furnace gases, and the like, particles held in mechanical suspension therein, and commonly known as "dust" or "flue dust."

My invention relates especially to a dust collector of that type in which the gases are caused to pass between closely disposed plates upon which the dust is deposited during such passage, the object of my invention being to provide simple and efficient means for effecting the discharge of the dust from the plates at any desired intervals, and also to provide for the convenient removal from the apparatus of the dust so discharged from the plates.

In the accompanying drawings—Figure 1 is a transverse section of my improved dust-collecting apparatus, the section being taken on the line *a—a*, Fig. 2; Fig. 2 is a horizontal section on the line *b—b*, Fig. 1; Fig. 3 is a longitudinal section on the line *c—c*, Fig. 2, of the casing of the apparatus without the dust collecting plates or the supporting devices therefor; Fig. 4 is a transverse section, on a larger scale than Fig. 1, and illustrating more clearly than in said figure the supporting devices for the dust collecting plates, and Fig. 5 is a horizontal section on a larger scale than Fig. 2, and illustrating more clearly than in said figure the means employed for subdividing the spaces between adjoining groups of dust collecting plates.

The structure has outer walls 1 which enclose a chamber of any desired shape and dimensions and intended for the reception of a series of groups of dust collecting plates each group comprising two series of superposed plates, the plates 2 of one series being inclined in one direction at any desired angle to the horizontal, and the plates 3 of the other series being inclined at a corresponding angle in the opposite direction. Alleyways 4 intervene between the groups of plates and also between the plates of the outermost groups and the outer wall of the furnace, these alleyways being preferably partitioned as hereinafter set forth.

The roof of the structure comprises a

series of sections, one for each group of collecting plates, the side wall 5 of each of these roof sections being preferably pitched to accord with the pitch or angle of the series of plates which it covers. Below each group of collecting plates, and extending throughout the length of the structure, is a chamber 6 comprising side walls 7 and a roof 8 pitched to accord with the angle of the plates of the group above the same, said side walls having therein passages 9 communicating with the adjacent alleyways 4.

The plates 2 and 3 of each group are mounted in any suitable way between central suspension rods 10 and side suspension rods 11, the means employed in the present instance for effecting such mounting being tapering collars 12 on the central rods, and lugs or hooks 13 projecting from sleeves 14 strung upon the side rods and retained in position vertically thereon by any suitable means. (See Fig. 4.)

The upper ends of the suspension rods 10 and 11 are mounted upon suitable supports above the roof of the furnace, such supports in the present instance consisting of pairs of I-beams 15 disposed back to back and mounted at their ends upon girders 16 carried by vertical columns 16^a, as shown in Fig. 3, each suspension rod passing freely between the pair of beams and having at its upper end a flange, collar, or like device, resting upon the upper flanges of the beams, as shown in Fig. 1.

Each of the suspension rods passes through an opening 17 in the roof of the furnace, this opening being of such dimensions as to permit of a slight side play of the rod therein and being luted or packed so as to prevent the escape of gas therethrough without interfering with such movement of the rod therein. The alleyways 4 are subdivided by plates 18 which are secured to and supported by ears 19 projecting from certain of the plate supporting collars 14 on the suspension rods 11, as best shown in Figs. 4 and 5.

Extending from one of the outer walls of the structure is a flue 20 communicating with the upper portion of the furnace 21 or other structure which supplies the gas from which the dust is to be separated, the opposite wall of the separator structure having a discharge outlet 22 which can communicate through a suitable discharge pipe

or flue with any point at which the cleaned gas is to be discharged or utilized. The flue 20 preferably flares in both directions so as to distribute the gas over as wide as possible an area on entering the chamber containing the dust collecting plates, and the discharge passage 22 is in line with the flaring inner end of the gas supplying flue 20.

10 The plates 2 and 3 present their ends to the current of gas entering the dust collecting chamber of the apparatus and the groups of plates present a multiplicity of passages through which the gas is caused to pass in its flow through said chamber, any flow through the alleyways 4 being prevented by reason of the stop plates 18 in said alleyways.

15 The gas passes through the channels between the plates 2 and 3 at relatively low speed so as to afford an opportunity for the deposit of the dust upon said plates, and in order to break up the direct flow of the gas through said channels the plates 2 and 3 are, 20 by preference, corrugated longitudinally, as shown in Fig. 2, so as to cause the gas currents to follow a wavy or zigzag course and thus tend to throw the dust toward the corrugated faces of the plates, the dust finally 25 settling upon the upper face of the plate at the bottom of the channel. Another function of the corrugations is to impart stiffness to the plates 2 and 3 so as to prevent them from sagging and insure the movement 30 of each plate substantially as a unit.

35 One of the principal difficulties encountered in the operation of dust collectors of the character to which my invention relates has been the removal of the accumulated dust from the faces of the plates, for, even 40 although the said plates may be disposed at an angle greater than the normal angle of repose of powdered granular material, the tendency of the fine particles of dust to cling 45 together and to the surface of the plate prevents the automatic discharge of the dust from the plate which would normally result if it was a free flowing body. I have found, 50 however, that if the plates are subjected to a shaking or jarring action, causing them to tremble, the hold of the deposited dust upon the plates will be loosened and the mass of dust will slide from each plate into the adjoining alleyway 4.

55 In order to impart the desired shaking or jarring motion to the separator plates, I find it sufficient to jar the supporting rods upon which the plates are suspended, a blow or succession of blows delivered upon the 60 portions of the rods 10 and 11 projecting above the roof of the apparatus being sufficient to impart such a tremor to the plates 2 and 3 as to cause dislodgment of the material which has accumulated thereon.

65 The material accumulating in the alley-

ways 4 can be withdrawn therefrom into the chambers 6 through the openings 9 in the side walls of said chambers, the dimensions of the chambers 6 being such as to accommodate the workmen who perform this duty. 70 To prevent said chambers from becoming uncomfortably hot the roofs 8 may be provided with a lining 25 of asbestos or other material which is a non-conductor or poor conductor of heat, and to prevent radiation 75 of heat from the roofs 5 of the apparatus the spaces between said roofs or between the same and the outer walls may be filled with any material which will thus restrict or prevent heat radiation.

80 Although I prefer in practice to use, in each group of dust collecting plates, two series of plates, one inclined in one direction and the other in an opposite direction, each group of plates may consist of but a single 85 series, if desired, and while I prefer also to mount the dust collecting plates upon supporting rods suspended from above, said plates may be otherwise supported, if desired, for example upon posts so mounted 90 that they will not be held rigidly and thus prevented from being jarred or agitated by blows upon them to such an extent as to transmit such agitation to the plates supported upon them. The jarring of one of 95 the supports or one row of supports for the series of plates may, in many cases, be sufficient to impart the desired shake or tremor to said plates.

100 I claim:

1. The combination, in a dust collector, of a casing containing a chamber having therein superposed, transversely inclined dust-retaining plates, means for passing dust-laden gases between said plates, rods at the 105 top and at the bottom of said plates upon which they are mounted, and means for suspending said rods at the top so that they can be jarred and caused to transmit to the plates vibrations for causing discharge of 110 the accumulated dust therefrom.

2. The combination, in a dust collector, of a casing having therein a chamber containing superposed, transversely inclined dust-retaining plates, means for passing dust-laden gases between said plates, rods at the top and other rods at the bottom of said plates upon which they are mounted, said bottom supporting rods being free at their lower ends, and means for suspending said 115 rods at the top so that they can be jarred in order to transmit to the plates vibrations for causing discharge of the accumulated dust therefrom.

3. A dust separator comprising a casing 120 having a chamber therein containing superposed, transversely inclined dust-retaining plates, means for passing dust-laden gases between said plates, and a supporting rod 125 for said plates having thereon flaring col- 130

lars against which the upper ends of the plates have a bearing.

4. A dust separator comprising a casing having a chamber therein containing superposed, transversely inclined dust-retaining plates, means for passing the dust-laden gases between said plates, and supporting rods at the lower ends of the plates, said rods having sleeves strung thereon, and said

sleeves having plate-supporting hooks projecting therefrom.

In testimony whereof, I have signed my name to this specification, in the presence of two subscribing witnesses.

UTLEY WEDGE.
